US00D960459S

(12) **United States Design Patent** (10) **Patent No.:** **US D960,459 S**
Jenkins et al. (45) **Date of Patent:** **** Aug. 9, 2022**

(54) **HEARING PROTECTION DEVICE**

(71) Applicant: **Honeywell International Inc.**, Charlotte, NC (US)

(72) Inventors: **John Jenkins**, San Diego, CA (US); **Scott Hutt**, San Diego, CA (US); **Wei Sun**, Shanghai (CN); **Yongjun Chen**, Shanghai (CN); **Lei Jiang**, Shanghai (CN)

(73) Assignee: **HONEYWELL INTERNATIONAL INC.**, Charlotte, NC (US)

(**) Term: **15 Years**

(21) Appl. No.: **29/816,393**

(22) Filed: **Nov. 22, 2021**

Related U.S. Application Data

(62) Division of application No. 29/680,788, filed on Feb. 20, 2019, now Pat. No. Des. 939,779.

(57) **CLAIM**

The ornamental design for a hearing protection device, as shown and described.

DESCRIPTION

FIG. 1 is a perspective view of a hearing protection device showing our new design;

FIG. 2 is another perspective view thereof;

FIG. 3 is another perspective view thereof;

FIG. 4 is a top plan view thereof;

FIG. 5 is another perspective view thereof;

FIG. 6 is a bottom plan view thereof;

FIG. 7 is a left side elevation view thereof;

FIG. 8 is a right side elevation view thereof;

FIG. 9 is a front elevation view thereof; and,

FIG. 10 is a rear elevation view thereof.

1 Claim, 9 Drawing Sheets
